UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

DESIGN FOR A SIGNALING DEVICE AND BRACKET THEREFOR.

43,053.

Specification for Design.

Patented Sept. 24, 1912.

Application filed October 9, 1911. Serial No. 653,718. Term of patent 7 years.

To all whom it may concern:

Be it known that I, RAY H. MANSON, a citizen of the United States, residing at Elyria, county of Lorain, and State of Ohio, have invented a new, original, and ornamental Design for Signaling Devices and Brackets Therefor, of which the following is a specification, reference being had to the accompanying drawing, forming a part thereof.

The figure is a side elevation of my improved design.

I claim:

The ornamental design for a signaling device and bracket therefor, as shown.

RAY H. MANSON.
